US00D889550S

(12) **United States Design Patent** (10) **Patent No.:** **US D889,550 S**
(45) **Date of Patent:** **** Jul. 7, 2020**

(54) **GAME CONTROLLER**

(71) Applicant: **Ironburg Inventions Limited**, Wincanton, Somerset (GB)

(72) Inventors: **Duncan Ironmonger**, Suwanee, GA (US); **Carl Jeffrey**, Gloucestershire (GB); **Michael Parker**, Gloucestershire (GB)

(73) Assignee: **Ironburg Inventions Limited**, Wincanton (GB)

(**) Term: **15 Years**

(21) Appl. No.: **29/662,365**

(22) Filed: **Sep. 5, 2018**

(51) LOC (12) Cl. **21-01**
(52) U.S. Cl. **USPC D21/333; D14/401**

(58) **Field of Classification Search**

USPC D14/174, 218, 387-389, 400-418,
D14/426-431, 443, 449-450, 454, 471,
D14/511; D21/333, 363, 368
CPC A63F 13/42; A63F 13/98; A63F 13/24;
G06F 3/0338
